UNITED STATES PATENT OFFICE.

LUMAN BIRCH WING, OF BROOKLYN, NEW YORK.

PNEUMATIC ACTION FOR AUTOMATIC PLAYING MECHANISMS.

1,290,461.

Specification of Letters Patent.

Patented Jan. 7, 1919.

Application filed June 19, 1915. Serial No. 35,115.

To all whom it may concern:

Be it known that I, LUMAN B. WING, a citizen of the United States, and a resident of the borough of Brooklyn, county of 5 Kings, in the city and State of New York, have invented certain new and useful Improvements in Pneumatic Actions for Automatic Playing Mechanisms, of which the following is a specification, reference being 10 made to the accompanying drawings, forming a part thereof.

My invention in its preferred embodiment relates to pneumatic actions and playing devices in automatic musical instruments of 15 that type in which a series of hammers are arranged to actuate the strings or keys of the piano or other musical instrument, said hammers being operated by means of power pneumatics and co-operating instrumentalities, the action of which is governed by a 20 perforated note-sheet passing over the orifices of the tracker, said sheet being provided with note perforations representing the musical score or composition.

My present improvements relate more 25 particularly to the control of the individual power pneumatics through the separate valves formed by the perforated sheet passing over the usual openings in the tracker, thereby opening and closing valves there- 30 with and doing away with the customary puppet valves for operating the primary pneumatics; and my improvements also involve a mechanism combined with such 35 pneumatic action for controlling and varying the intensity of the hammer stroke on the strings or keys through the action of the bellows or pumping device for actuating the playing mechanism as a whole.

The objects of my invention, among other 40 things, are to simplify and improve the construction and arrangement of the parts comprising the individual pneumatic action and parts connected therewith, so as to insure 45 the requisite duration, rapidity and intensity of the hammer stroke, to regulate the tone through the pumping bellows, and to so construct the whole that it will be simple, compact and durable in all its parts, accurate 50 and efficient in its movements, and not liable to get out of order.

To accomplish this, my improvements involve certain novel and useful peculiarities of construction, relative arrangements and

connection of parts and principles of operation, all of which will be herein first fully described and then pointed out in the claims. 55

In the drawings, Figure 1 is a view of the top of the tracker with the perforated note-sheet passing over it; Fig. 2 is a vertical fore-and-aft side view, of a pneumatic action embodying my invention, the same being shown in connection with the hammer action of a piano; Fig. 3 is a perspective view 60 of the arrangement of the individual pneumatic actions; Fig. 4 is a vertical sectional view of the pneumatic and slide valve regulating mechanism; Fig. 5 is a detail view 65 of part of the sliding valve; and Fig. 6 is a vertical cross-sectional view of the pneumatic action shown in Fig. 2. 70

Similar numerals refer to similar parts throughout the several views.

Referring to the drawings, 6 is the tracker-bar of ordinary construction with the usual 75 openings or air ducts 7 adapted to register with the perforations 8 cut in the note-sheet 9 as shown in Fig. 1. The tracker 6 is shown in its usual relation to the music 80 roll 10 and take-up roll 11, located in the spool-box 12. From the tracker 6 the air ducts 7 in the form of flexible tubes 13 lead directly to a row or series of control pneumatics 14, preferably fastened under the front margin of the shelf 15 as shown in 85 Figs. 2 and 3. Running transversely along the upper margin of the shelf 15, is the hollow channel board 16 connected by the tube 17 with any suitable exhaust apparatus, not shown, thereby forming the exhaust chamber 90 18, extending across the front of the shelf 15. The series of control pneumatics 14 are each connected with the exhaust chamber 18 by suitable ports 19 having therein bleed-holes 20 of usual construction, as shown in 95 Fig. 6.

Along the upper rear side of the shelf 15 is located the hollow channel board 21, of substantially similar construction as the channel board 16, forming the exhaust chamber 22 which is connected with the exhaust apparatus by the tube 23. The location and arrangement of the respective channel boards 16 and 21 and exhaust chambers 18 and 22 on the shelf 15 are clearly shown in Figs. 100 105 2 and 3.

Beneath the rear edge of the shelf 15 are secured a corresponding row or series of

power pneumatics 24, corresponding in number with the series of control pneumatics 14 and arranged in transverse parallelism therewith. These power pneumatics 24 are each 5 connected with the exhaust chamber 22 by separate ports 25, as shown in cross section in Fig. 6. The movable leaves of the two pneumatics 14 and 24 in any individual pneumatic action showing my improvement are connected 10 by the control lever 26, fulcrumed at the hinge joint of the power pneumatic 24, as shown in Fig. 6. The location and connection of pneumatics and control levers are such that the power of the control pneumatic 14 is 15 greater on the left end of the lever 26 than that exerted by the pneumatic 24, when the connecting air duct 7 in the tracker 6 is closed by the note-sheet 9, the position of the lever 26 being shown in full lines in Fig. 20 6, and in dotted lines when the air duct 7 is open to atmospheric pressure, thereby changing the status of the two pneumatics.

The inner end 27 of the lever 26 acts upon the piano hammer action as shown in Fig. 25 2, by striking the felt faced lug 28 affixed to the abstract 29 which actuates the wippen 30 to operate the hammer 31 through the medium of the hopper jack 32 and hammer butt 33. In order to adjust the connections 30 from each power pneumatic 24 to the wippen connection on which it operates according to the necessities of the case, there is provided a regulating rail 34 in which there are separate adjustable screw stops 35 to 35 limit the upward movement of the lug 28, thereby controlling with exactness the stroke of the separate power pneumatics 24 in operating the instrument.

Referring now to Figs. 4 and 5, I have 40 here shown my improved construction devised to control and vary the intensity of such hammer stroke on the strings or keys of the piano equipped with my pneumatic action hereinbefore described by the action 45 of the foot-bellows or pumping device. In this improvement the following detail features should be noted as characteristic of the device. Between the bellows 58 and the separate exhaust chambers 18 and 22 a regulating pneumatic 36 is interposed normally held expanded by a spring or other means, combined with a double slide-valve actuated by the pneumatic 36 to vary the comparative tensions in the separate exhaust chambers 50 18 and 22, thereby directly controlling by the pumping device the accentuation of the notes that are being played. The pneumatic 36 is connected with the pumping device or bellows 58, by the tube 37; the 55 movable leaf 38 of the pneumatic 36 when collapsed strains a suitable coil-spring 39 or other device, which is adjusted to the force of the collapsing pneumatic as experience may determine. Attached to the 60 movable leaf 38 is the swinging arm 40

extending between two valve boxes 41 and 42 connected with the exhaust chambers 18 and 22 respectively by the tubes 17 and 23 respectively, and with the pumping bellows 58, by the tubes 43 and 44 respectively. 70 Each valve box 41 and 42 has a horizontal plate 45 and 46 respectively located therein in which suitably arranged slots 47 and 48 are respectively cut, which slots are opened and closed by the sliding valves 49 and 50 75 respectively. The valves 49 and 50 are connected by the rod 51 which is secured to the end of the arm 40, and are thereby horizontally operated by the pneumatic 36. When the pneumatic 36 is expanded, as 80 shown in Fig. 4, the left hand slot 47 is wide open and the right hand slot 48 is nearly closed; when the pneumatic 36 is collapsed as against the coil spring 39 through high-tension in the pumping bellows 58, 85 the slot 48 is entirely open while the slot 47 is nearly closed. It is obvious that the operator through the expansion and collapsing of this pneumatic 36 in varying the operation of the pumping bellows, may directly 90 vary and control the respective air tensions in the respective exhaust chambers 18 and 22, thereby varying the intensity and force 95 of the hammer stroke on the strings or keys of the piano action proper equipped with my pneumatic action hereinbefore described.

In operation, when the tracker air ducts 7 are opened by a note-sheet perforation registering with the proper air duct in the 100 tracker, air at atmospheric pressure expands the control pneumatic 14, breaking the equilibrium maintained by the control lever 26 between the closed control pneumatic 14 and the open power pneumatic 24, and causes the power pneumatic 24 immediately 105 to collapse, as shown in the dotted lines in Fig. 6, whereby the inner end 27 of the lever 26 strikes an upward blow on the lug 28 of the hammer action. When the tracker duct 110 7 is again covered by the unperforated part of the note-sheet, the control pneumatic 14 is at once collapsed, and through the greater leverage of the longer arm of the control lever 26, the power pneumatic 24 is expanded, and the normal equilibrium maintained by the sheet 9 forming a closed valve with the tracker duct 7 renders the power pneumatic 24 inoperative.

It is apparent that my improved pneumatic action does away entirely with the customary primary and secondary pneumatics of the usual diaphragm type, since I utilize the traveling note-sheet itself to coöperate with the air ducts 7 in the tracker 6 itself to form the separate valves directly controlling through the control pneumatic 14, the separate power pneumatics 24 for operating the piano action.

Another embodiment of my invention is 130

shown in Fig. 2, where a spring valve, operated manually or otherwise, is utilized in lieu of the perforated note-sheet and tracker to form the control valve. Such form of valve is illustrated in conjunction with an "expression-device" for regulating the range of movement of the hammer 31. The rail 52 rocks on the pivot 53 through the lug 54 and link 55 connected with the end 27 of the control lever 26, affixed to the pneumatics 14 and 24 as hereinbefore described. The button 56, when depressed, opens the spring valve 57, which is directly connected with the pneumatic 14 by the tube 13, in the same manner as the perforated sheet opens and closes the air ducts 7 on the tracker 6. The position of the rail 52 with respect to the arm of the hammer 31 may be shifted thereby at will.

I have described my invention as being operated by the partial vacuum principle, but I do not limit myself thereto, as the pneumatic actions may be operated by air under pressure. I prefer, however, to utilize an air-exhaust apparatus as hereinbefore described, which is customary in automatic musical instruments.

Many other modified arrangements of this device may be employed adapted to the requirements of different conditions or different instruments and machines in many ways that will obviously occur to those familiar with this art.

I claim as my invention:

1. A pneumatic action comprising a control pneumatic, a power pneumatic, a separate exhaust chamber connected with each pneumatic, means connecting the movable members of both pneumatics, and means for varying the air tensions in the two pneumatics to operate said action.

2. A pneumatic action comprising a control pneumatic, a power pneumatic, a separate exhaust chamber connected with each pneumatic, means rigidly affixed to the movable members of both pneumatics, and means for varying the air tensions in the two pneumatics to operate said action.

3. A pneumatic action comprising a control pneumatic, a power pneumatic, a separate exhaust chamber connected with each pneumatic, means connecting the movable members of both pneumatics, the control pneumatic being maintained in a collapsed position while the power pneumatic is maintained in an expanded position, and means for varying the air tensions in the two pneumatics to operate said action.

4. A pneumatic action comprising a control pneumatic, a power pneumatic, a separate exhaust chamber connected with each pneumatic, means connecting the movable members of both pneumatics, the control pneumatic being maintained in a collapsed position while the power pneumatic is main-

tained in an expanded position, and means for varying the air tensions in the two pneumatics to reverse the positions of said pneumatics.

5. A pneumatic action comprising a control pneumatic, a power pneumatic, a separate exhaust chamber connected with each pneumatic, means rigidly affixed to the movable members of both pneumatics, the control pneumatic being maintained in a collapsed position while the power pneumatic is maintained in an expanded position, and means for varying the air tensions in the two pneumatics to operate said action. 70

6. A pneumatic action comprising a control pneumatic, a power pneumatic, a separate exhaust chamber connected with each pneumatic, means rigidly affixed to the movable members of both pneumatics, the control pneumatic being maintained in a collapsed position while the power pneumatic is maintained in an expanded position, and means for varying the air tensions in the two pneumatics to operate said action. 80

7. A pneumatic action comprising a control pneumatic, a power pneumatic, a separate exhaust chamber, connected with each pneumatic, means connecting the movable members of both pneumatics, both pneumatics being maintained in inoperative position, and means for varying the air tensions in the control pneumatic to reverse the positions of said pneumatics. 90

8. The combination, with a perforated note-sheet, of a tracker having air-ducts, of a pneumatic action comprising a control pneumatic directly connected with an air duct, a power pneumatic, and means connecting the movable members of both pneumatics to operate a player action when a note-sheet perforation registers with the tracker-duct connected with the control pneumatic. 100

9. The combination, with a perforated note-sheet, of a tracker having air-ducts, and a pneumatic action comprising a control pneumatic directly connected with a tracker duct, a power pneumatic to operate a player action, means connecting the movable members of both pneumatics, the former pneumatic maintained in a collapsed position while the latter is maintained in an expanded position by the unperforated portions of the sheet, for operating a player action when the note-sheet perforation registers with a tracker duct connected with said control pneumatic. 110

10. The combination, with a perforated note-sheet, of a tracker having air-ducts, of a pneumatic action comprising a control pneumatic directly connected with an air duct, a power pneumatic and a lever affixed to the movable members of both pneumatics to operate a player action when a note-sheet 125

perforation registers with the tracker-duct connected with the control pneumatic.

11. The combination, with a perforated note-sheet, of a tracker having air-ducts, of 5 a pneumatic action comprising a control pneumatic directly connected with an air duct, a power pneumatic, and a lever affixed to the movable members of both pneumatics and fulcrumed on the hinge of the power 10 pneumatic with the longer arm affixed to the control pneumatic, to operate a player action when a note-sheet perforation registers with the tracker-duct connected with the control pneumatic.

15 12. The combination, with a perforated note-sheet, of a tracker having air-ducts, of a pneumatic action comprising a control pneumatic directly connected with an air duct, a power pneumatic to operate a player 20 action, rigid means connecting the movable members of both pneumatics, and an exhaust chamber connected with said pneumatics, both pneumatics being maintained in inoperative position by the unperforated portions 25 of the sheet, for operating the player action when a note-sheet perforation registers with a tracker duct connected with said control pneumatic.

13. The combination, with a perforated 30 note-sheet, of a tracker having air-ducts, and a pneumatic action comprising a control pneumatic connected with a tracker-duct, a power pneumatic to operate a player action, a lever fulcrumed on the power pneumatic to 35 operatively connect said control pneumatic with said power pneumatic, both pneumatics being maintained in inoperative position by the unperforated portions of the sheet and becoming operative when a note-sheet perforation registers with the tracker-duct connected with said control pneumatic.

14. The combination, with a perforated note-sheet, of a tracker having air-ducts, and a pneumatic action comprising a control 45 pneumatic connected with a tracker-duct, a power pneumatic to operate a player action, a lever fulcrumed on the power pneumatic to operatively connect said control pneumatic with said power pneumatic, the control 50 pneumatic being maintained in a collapsed position and the power pneumatic in an expanded position by the unperforated portions of the sheet, and both pneumatics reversing their position when a note-sheet perforation registers with the tracker-duct connected with said control pneumatic.

15. A pneumatic action comprising in 60 combination with a perforated note-sheet and tracker having air-ducts, a control pneumatic connected with a tracker-duct, an exhaust chamber, a power pneumatic to operate a player action, means for connecting both pneumatics with the exhaust chamber, and means connecting the movable members 65 of both pneumatics to operate the player ac-

tion when a note-sheet perforation registers with the tracker-duct connected with said control pneumatic.

16. A pneumatic action comprising in combination with a perforated note-sheet 70 and tracker having air-ducts, a control pneumatic connected with a tracker-duct, an exhaust chamber, a power pneumatic to operate a player action, means for connecting both pneumatics with the exhaust chamber, 75 and lever means affixed to the movable members of both pneumatics to operate the player action when a note-sheet perforation registers with the tracker-duct connected with said control pneumatic. 80

17. A pneumatic action comprising in combination with a perforated note-sheet and tracker having air-ducts, a control pneumatic connected with a tracker-duct, an exhaust chamber, a power pneumatic to operate a player action, means for connecting both pneumatics with the exhaust chamber, and a lever affixed to the movable members of both pneumatics, and fulcrumed on the hinge of the power pneumatic to operate the 90 player action when a note-sheet perforation registers with the tracker-duct connected with said control pneumatic. 85

18. A pneumatic action comprising in combination with a perforated note-sheet 95 and tracker having air-ducts, a control pneumatic connected with a tracker-duct, an exhaust chamber, a power pneumatic to operate a player action, means for connecting both pneumatics with the exhaust chamber, 100 and a lever affixed to the movable members of both pneumatics and fulcrumed on the hinge of the power pneumatic with the longer arm affixed to the control pneumatic, to operate the player action when a note- sheet perforation registers with the tracker-duct connected with said control pneumatic. 105

19. In a pneumatic action, the combination with a pumping bellows, of two exhaust chambers connected with the pneumatic action, a pneumatic directly operable by said bellows and yieldingly held in an expanded position when the air pressure in the bellows is at low tension, and means interposed between said bellows and said exhaust 110 chambers, operable by said pneumatic, to vary the difference in air pressure in the two exhaust chambers when the position of said pneumatic is changed through increased tension in the bellows. 115

20. In a pneumatic action, the combination with a pumping bellows, of two exhaust chambers connected with the pneumatic action, a control pneumatic directly operable by said bellows, a spring to yieldingly hold 125 said control pneumatic open when the air pressure in the bellows is at low tension, means interposed between said bellows and said exhaust chambers, operable by said pneumatic to vary the difference in air pres- 130

sure in the two exhaust chambers when the position of said control pneumatic is changed through increased tension in the bellows.

21. In a pneumatic action, the combination with a pumping bellows, of two exhaust chambers connected with the pneumatic action, a pneumatic directly operable by said bellows and yieldingly held in an expanded position when the air pressure in the bellows is at low tension, and separate valves interposed between said bellows and each of said exhaust chambers, jointly operable by said pneumatic to vary the difference in air pressure in the two exhaust chambers when the position of said control pneumatic is changed through increased tension in the bellows.

22. In a pneumatic action, the combination with a pumping bellows, of two exhaust chambers connected with the pneumatic action, a control pneumatic directly operable by said bellows, a spring to yieldingly hold said control pneumatic open when the air pressure in the bellows is at low tension, and separate valves interposed between said bellows and each of said exhaust chambers, jointly operable by said pneumatic to vary the difference in air pressure in the two exhaust chambers when the position of said control pneumatic is changed through increased tension in the bellows.

23. In a pneumatic action, the combination with a pumping bellows, of two exhaust chambers connected with the pneumatic action, a pneumatic directly operable by said bellows and yieldingly held in an expanded position when the air pressure in the bellows is at low tension, and a double-sliding valve action interposed between said bellows and each of said exhaust chambers, secured to and operated by said pneumatic to vary the difference in air pressure in the two exhaust chambers when the position of said control pneumatic is changed through increased tension in the bellows.

24. In a pneumatic action, the combination with a pumping bellows, of two exhaust chambers connected with the pneumatic action, a control pneumatic directly operable by said bellows, a spring to yieldingly hold said control pneumatic open when the air pressure in the bellows is at low tension, and a double-sliding valve action interposed between said bellows and each of said exhaust chambers, secured to and operated by said pneumatic to vary the difference in air pressure in the two exhaust chambers when the position of said control pneumatic is changed through increased tension in the bellows.

25. In combination with a pneumatic action comprising a control pneumatic and a power pneumatic each connected with separate exhaust chambers, of a pumping bellows, a pneumatic directly operable by said bellows and yieldingly held in an expanded

position when the air pressure in the bellows is at low tension, and means interposed between said bellows and said exhaust chambers, operable by said pneumatic to vary the difference in air pressure in the two exhaust chambers when the position of said pneumatic is changed through increased tension in the bellows.

26. In combination with a pneumatic action comprising a control pneumatic and a power pneumatic each connected with separate exhaust chambers, of a pumping bellows, a control pneumatic directly operable by said bellows, a spring to yieldingly hold said control pneumatic open when the air pressure in the bellows is at low tension, means interposed between said bellows and said exhaust chambers, operable by said pneumatic to vary the difference in air pressure in the two exhaust chambers when the position of said control pneumatic is changed through increased tension in the bellows.

27. In combination with a pneumatic action comprising a control pneumatic and a power pneumatic each connected with separate exhaust chambers, of a pumping bellows, a pneumatic directly operable by said bellows and yieldingly held in an expanded position when the air pressure in the bellows is at low tension, and separate valves interposed between said bellows and each of said exhaust chambers, jointly operable by said pneumatic to vary the difference in air pressure in the two exhaust chambers when the position of said control pneumatic is changed through increased tension in the bellows.

28. In combination with a pneumatic action comprising a control pneumatic and a power pneumatic each connected with separate exhaust chambers, of a pumping bellows, a control pneumatic directly operable by said bellows, a spring to yieldingly hold said control pneumatic open when the air pressure in the bellows is at low tension, and separate valves interposed between said bellows and each of said exhaust chambers, jointly operable by said pneumatic to vary the difference in air pressure in the two exhaust chambers when the position of said control pneumatic is changed through increased tension in the bellows.

29. In combination with a pneumatic action comprising a control pneumatic and a power pneumatic each connected with separate exhaust chambers, of a pumping bellows, a pneumatic directly operable by said bellows and yieldingly held in an expanded position when the air pressure in the bellows is at low tension, and a double-sliding valve action interposed between said bellows and each of said exhaust chambers, secured to and operated by said pneumatic to vary the difference in air pressure in the two exhaust chambers.

haust chambers when the position of said control pneumatic is changed through increased tension in the bellows.

30. In combination with a pneumatic action comprising a control pneumatic and a power pneumatic each connected with separate exhaust chambers, of a pumping bellows, a control pneumatic directly operable by said bellows, a spring to yieldingly hold 10 said control pneumatic open when the air pressure in the bellows is at low tension, and a double-sliding valve action interposed between said bellows and each of said exhaust chambers, secured to and operated by said 15 pneumatic to vary the difference in air pressure in the two exhaust chambers when the position of said control pneumatic is changed through increased tension in the bellows.
20. 31. A pneumatic action comprising a control pneumatic, a power pneumatic, a separate exhaust chamber connected with each pneumatic, a lever affixed to the movable members of both pneumatics, and means for 25 varying the air tensions in the two pneumatics to operate said action.

32. A pneumatic action comprising a control pneumatic, a power pneumatic, a separate exhaust chamber connected with each 30 pneumatic, a lever affixed to the movable members of both pneumatics, and fulcrumed on the hinge of the power pneumatic with the longer arm affixed to the two pneumatics, and means for varying the air 35 tensions in the control pneumatic to operate said action.

Copies of this patent may be obtained for five cents each, by addressing the "Commissioner of Patents, Washington, D. C."

33. In a pneumatic action, the combination with a pumping bellows, of two exhaust chambers connected with the pneumatic action, a pneumatic operable by said bellows 40 and yieldingly held in an expanded position when the air pressure in the bellows is at low tension, and means, operable by the movement of said pneumatic, through increased tension in the bellows, to vary the 45 difference in air pressure in the two exhaust chambers.

34. In combination with a pneumatic action comprising a control pneumatic and a power pneumatic each connected with separate 50 exhaust chambers, of a pumping bellows, a pneumatic operable by said bellows and yieldingly held in an expanded position when the air pressure in the bellows is at low tension, and means, operable by the 55 movement of said pneumatic through increased tension in the bellows, to vary the difference in air pressure in the two exhaust chambers.

35. A pneumatic action comprising a control pneumatic, a power pneumatic, the leaves of both pneumatics constituting a movable lever to operate the action, a separate exhaust chamber connected with each pneumatic, and means for varying the relative 60 air tensions in the two pneumatics to actuate said lever.
